UNITED STATES PATENT OFFICE.

JAMES G. THORSTENSEN, OF CLINTON, MINNESOTA.

WASHBOARD.

Application filed July 12, 1922. Serial No. 574,353.

To all whom it may concern:

Be it known that I, JAMES G. THORSTENSEN, a citizen of the United States, residing at Clinton, in the county of Bigstone and 5 State of Minnesota, have invented certain new and useful Improvements in Washboards, of which the following is a specification.

This invention relates to new and useful 10 improvements in a washboard and has for its principal object to provide a washboard with a rough board for the purpose of easily facilitating the scrubbing of clothes placed upon the washboard.

15 Another object of the invention is to provide a washboard of the above mentioned character wherein the same is adapted to slidably support a rub board for the purpose of more easily rubbing the clothes placed 20 upon the washboard and which is further easily operated.

25 A still further object of the invention is to provide a washboard of the above mentioned character which is simple in construction, strong and durable and inexpensive to manufacture.

30 Other objects and advantages of the invention will become apparent during the course of the following description.

35 In the accompanying drawings forming a part of the description and wherein like numerals designate like parts throughout the several views:—

Figure 1 is a front elevation of the washboard with the rub board applied thereon.

Figure 2 is a side elevation of the invention, and

Figure 3 is a top plan view of the same.

In the drawings forming a part of the 40 specification, the numerals 1 and 2 designate the side rails of the washboard. The side rails 1 and 2 of the washboard are connected at their upper ends by means of a cross bar 3. A suitable rubbing surface 4 is supported 45 in the washboard between the side rails 1 and 2 and also at the top by means of the cross bar 3. This rubbing surface 4 consists of the usual corrugated sheet of metal although I do not wish to confine myself to 50 this specific type of rubbing surface. Extending longitudinally on the side rails 1 and 2 of the washboard and on the front face thereof are the guide rods 5 and 6. These guide rods 5 and 6 are embedded at 55 their lower ends in the side rails 1 and 2

respectively and at their top into the cross bar 3. This is more clearly illustrated in Figs. 1 and 2 of the drawings.

A rub board 7 is adapted to fit between the side rails 1 and 2 of the washboard and 60 carried by the underside of the rub board 7 is a rubbing surface similar to the rubbing surface carried by the washboard and between the side rails 1 and 2 for the purpose of engaging the rubbing surface carried by the side rails 1 and 2. This rubbing surface carried by the under side of the rub board 7 is illustrated at 8 in Fig. 1 of the drawing and is of the same material as used in the first mentioned rubbing surface. 65 Secured to the upper and lower edges of the rub board 7 are the plates 9 and 10 respectively. These plates 9 and 10 are secured to the rub board by any suitable fastening means 11. The plates 9 and 10 which are 70 carried by the rub board 7 are provided with laterally extending apertured ears 12 at adjacent ends for the purpose of allowing the rub board 7 to slide over the rubbing surface 4 between the guide rods 5 and 6 of 75 the washboard. At the opposite ends of the plates 9 and 10 are formed hook portions 13. These hook portions and ears are adapted to engage the guide rods 5 and 6 respectively 80 carried by the side rails 1 and 2 of the washboard. A handle 14 is provided upon the outer face of the rub board 7 and is mounted in suitable handle supporting elements 15 which are secured to the sides of the frame 85 of the rub board 7.

In use, the rub board 7 is swung away 90 from the washboard by means of disengaging the hooks 13 from guide rod 5 of the side rail 1, and the clothes to be rubbed are then placed upon the rubbing surface 4 carried 95 by the washboard and between the side rails 1 and 2 and after the clothes have been placed upon the rubbing surface 4, the rub board 7 is then clamped down upon the clothes in such a manner that the hooks 13 100 will engage the guide rod 5 and thereby hold the same in position, and as the rub board 7 is provided with apertured ears 12 so as to allow the rub board to reciprocate over the washboard and is further guided by the 105 apertured ears 12 and the hook portions 13 formed on the rub board 7 to prevent accidental displacement or relative movement laterally of the rub board 7 while in operative position upon the washboard. By mere- 110

ly operating the handle 14, the same causes the rub board 7 to freely reciprocate over the washboard and between the side rails 1 and 2 thereof and it will thus be seen that the 5 clothes may be easily and more quickly rubbed than is now the case of rubbing clothes by hand. The water will also drain off of the rubbing surface 4 to the receptacle into which the washboard and rub board 10 are placed, and therefore it will be seen that a new and useful improvement has been invented for the purpose of easily aiding in rubbing the clothes while in the process of washing the same, and also preventing the 15 person operating the device from injuring her hands in any manner.

It is to be understood that the form of my invention herewith shown and described is to be taken as the preferred embodiment of 20 the same, and that various changes in the shape, size and arrangement of parts may be resorted to without departing from the spirit of the invention or the scope of the subjoined claims.

25 Having thus described my invention what I claim is:—

1. The combination with a washboard frame having side rails, a rubbing surface supported by the said side rails, guide rods 30 extending longitudinally on the side rails, a

rub board arranged between the side rails, said rub board provided with a plate on each of its lower and upper ends, said plates each having an apertured extension at one end, and a hook portion at its opposite end for 35 slidably mounting the same upon the guide rods, and rubbing means carried by the rub board for engagement with the rubbing surface.

2. The combination with a washboard 40 frame having side rails, a rubbing surface supported by the said side rails, guide rods extending longitudinally on the said side rails, a rub board mounted on the washboard frame and between the said side rails, said rub board provided with plates at its upper and lower ends, said plates having apertured ears formed at one end for slidably and hingedly connecting the rub board upon one of the guide rods, hook portions carried 45 by the opposite ends of the plates for engagement with the other guide rod, and rubbing means carried by the rub board for engagement with the rubbing surface.

50 In testimony whereof I affix my signature 55 in presence of two witnesses.

JAMES G. THORSTENSEN.
